UNITED STATES PATENT OFFICE.

FRED HABENSACK, OF SAG HARBOR, NEW YORK, ASSIGNOR TO FAHYS
WATCH-CASE COMPANY, OF NEW YORK, N. Y.

DESIGN FOR A SPOON OR FORK HANDLE.

SPECIFICATION forming part of Design No. 34,858, dated July 30, 1901.

Application filed June 29, 1901. Serial No. 66,619. Term of patent 3½ years.

To all whom it may concern:

Be it known that I, FRED HABENSACK, a citizen of the United States, residing at Sag Harbor, in the county of Suffolk and State of New York, have invented and produced a new and original Design for Spoon and Fork Handles, of which the following is a specification, reference being had to the accompanying drawings, in which—

o Figure 1 shows the obverse side of a spoon, and Fig. 2 the reverse side thereof, bearing my new design, the tines of the fork being shown in dotted lines.

The leading or characteristic feature of my design consists of the outline or contour of the handle, formed by intertwining leaves, which leaves at the lower end of the handle form a fanciful scroll and which at a certain point in their length are spread or separated

o to inclose or surround a flower, from which latter the leaves separate or diverge in compound curves to form the border for the upper and widened end of the handle, partially inclosing or surrounding flowers and crossing and recrossing at their extreme upper ends to form a scroll.

Referring to the drawings, A represents

the handle of a spoon or fork, the lower portion of which is formed of leaves B, which at the extreme lower end of the handle end in a 30 fanciful scroll C. At a certain point in their length the leaves diverge and cross and recross, as illustrated at D, surrounding the flower E. Again diverging the leaves form a border F for the upper widened end of the 35 handle and partially surround the flowers G, the extreme ends of the leaves forming a scroll H.

In Fig. 2 is shown the reverse side of the handle decorated in harmony with the obverse side—that is, the lower extreme ends of the leaves J intertwining to form the scroll I, said leaves crossing and recrossing at K and forming the border for the upper widened 45 end of the handle and merging into the leaves L and scroll M.

What I claim is—

The design for a spoon or fork handle, substantially as shown and described.

FRED HABENSACK.
